United States Patent Office

Des. 178,893
Patented Oct. 2, 1956

178,893

ULTRAVIOLET LAMP

Tucker P. Madawick, Westport, Conn., and Earl F. Rutan, Pound Ridge, N. Y., assignors to Hanovia Chemical & Mfg. Company, Newark, N. J., a corporation of New Jersey

Application March 1, 1956, Serial No. 40,424

Term of patent 14 years

(Cl. D48—20)

The figure is a perspective view of an ultraviolet lamp, showing our new design.

We claim:

The ornamental design for an ultraviolet lamp, as shown.

References Cited in the file of this patent

UNITED STATES PATENTS

D. 54,429	Macbeth	Feb. 10, 1920
D. 76,542	Johnson	Oct. 9, 1928
D. 131,143	Bramsen	Jan. 20, 1942
D. 170,925	Kaveckas	Nov. 24, 1953
1,744,370	Dietz et al.	Jan. 21, 1930